UNITED STATES PATENT OFFICE

2,656,800

PIPE LAYING APPARATUS

Francis M. Reising, Edinburg, Tex.

Application May 2, 1946, Serial No. 666,717

1 Claim. (Cl. 111—5)

1

This invention relates to improvements in a traveling shoring box for use in association with ditching machines of various types.

One of the objects of this invention is to provide a shoring box capable of transverse adjustment for use in connection with ditching and laying of pipe, regardless of the size of the ditch or the type of pipe to be laid.

Another object of the invention is to construct an adjustable shoring box having grooving or channeling means for forming a channel for the pipe to be laid medially of the ditch floor.

A further object of the invention is the provision of a hoist removably mounted at the top of the shoring box to facilitate the handling of pipe.

A still further object of the invention is to provide a mounting for the hoist of such character that this mounting will be retained centrally of the shoring box body regardless of the lateral adjustment of the box.

Other features and objects will more fully hereinafter appear by reference to the accompanying drawing forming a part of this specification and wherein like characters of reference designate corresponding parts throughout the several views, in which:

Fig. 1 is a side elevation showing the invention in operative relation to a ditching machine.

Fig. 2 is a perspective view of the invention.

Fig. 3 is a transverse section on line 3—3 of Figure 2.

Fig. 4 is a transverse section on line 4—4 of Figure 2, and

Fig. 5 is a fragmentary perspective showing the forward end of the shoring box.

In Figure 1 a conventional ditching machine is illustrated by reference character A, this machine including the ditching head B which forms the ditch or cut generally indicated by reference character C. A cable D connects the ditching machine A with the shoring box, the latter being shown more fully in Figure 2.

The shoring box embodies a pair of spaced rectangular frames each including horizontal side angle members 1 and connecting vertical angle members 2. The weight of the metal used in forming these frames and the depth of the flanges of the angle members will be a matter determined by the size of the box. Vertical stays or struts 3 may be suitably arranged to reinforce the outer frame structure, this frame structure in instances being subject to external pressure due to cave-ins from the wall of the ditch. In forming the two spaced frames the joints between the vari-

2

ous parts may be secured by riveting or welding, or with bolts in instances where the structure is to be made in knocked-down form. Side sheeting 4 extends between the uprights 2 and substantially close the side walls of the shoring box. In fact, these side walls may be entirely closed and the side sheets 4 may be secured to the frame by rivets, bolts or by welding as desired.

The front end of the shoring box is connected by overlapping plates 6 and 7 and 9 and 10, the latter plates 9 and 10 extending between the uprights 2 adjacent the upper end thereof while the lower plates 6 and 7 extend from a point approximately the center of the uprights down to the lower marginal edge as shown in Figure 5. The overlapping plates 6, 7, 9 and 10 are formed with aligned slots 11 and through these slots bolts 12 extend and are secured by nuts 14, more clearly shown in Figure 4. In the disclosure forming a part of this application the connecting plates 6, 7, 9, and 10 are welded to the corner uprights 2 although other methods of securing these parts together may be found desirable in some instances. The outer lower plate 6 has secured at its lower outer face the shovel 15, this shovel including the flat shank 16 and the rounded plow face 17, the latter being used for fine grading of the surface area in which the pipe sections are to be laid, as will be more clearly hereinafter described. The shovel 15 is secured by bolts 18 or other suitable means and is adjustable by means of slots so that this shovel may be retained centrally of the assembly and the pipe channel properly positioned, in the event the sides of the structures are relatively adjusted. A connecting plate or bar 20 extends between the front uprights 2 and this bar 20 may be shifted vertically with respect to these uprights by use of the bolts 21 cooperating with the openings 22 in the channels 2. In this manner the angle of drag from the power shovel can be varied in order to keep the structure in a horizontal plane in its movement following the digger head B. It will be noted that the connecting cable D between the digger A and the shoring box is thus readily shifted and the stress properly distributed by suitable manipulation of the parts. The eyelet 23 of the cross bar 20 forms the connection with the cable D and the cable may have a hook or other separable fastener to facilitate adjustments.

The rear end of the shoring box is connected adjacent the bottom edges by the plates 24 and 25, while the upper portion of the rear end of this structure is connected by the adjustable

plates 26 and 27. These plates may be of any width and are connected with the bolt 11' and slot connections 12', similar to the bolt and slot connections used at the front of the structure and as shown in Figure 4.

The top of the shoring box includes the inwardly projecting plates 30 and 31 connected to the horizontal flanges of the top angle bars 1, by welding, rivets, or otherwise and these inwardly projecting horizontal plates 30 and 31 are formed with aligned slots 32 at spaced intervals for use in connecting thereto the intermediate plate 33. The plate 33 overlies, along its longitudinal marginal edges, the slotted portions of the plates 30 and 31 and the bolts 34 carried by the plate 33 extend through the slot 32 and clamp the parts together in any desirable adjustable position, corresponding to the adjustment of the end connections heretofore described.

Supported upon the plate 33 is the supporting frame 35 providing a pedestal structure including the pedestal cap 36 upon which is rotatably mounted the plate 37 of the hoist frame 38. The hoist frame 38 is of conventional form and includes the hoist arm 39 with suitable pulley 40 for the cable 41. The cable 41 is provided with a pipe hook 42 at its free end, while the other end of the cable is controlled by the hoisting mechanism 43 which may be manually operated, and provided with the usual pawl and ratchet control. This hoist structure is to facilitate the handling and movement of the pipe from the side of the ditch into the shoring box where it is manually laid in position in the channel formed by the plow 15 as is more fully hereinafter described.

Along the upper marginal edge of the shoring box a plurality of projections 46 are arranged in spaced relation to provide a rack for receiving and retaining pipe sections as shown at 47.

In use and operation of a shoring box of the type above described it is of paramount importance that the structure operate to form a fin-

ished channel in a ditch at a predetermined level with respect to the earth's surface and I have provided means for accomplishing this purpose including a main gauge supporting frame 50 having depending arm 51 for supporting the balanced transverse rod 51' carrying the contact member 51''. Associated movement in relation to a shifted cable 52 is thus provided at a predetermined level.

I claim:

In a shoring box a pair of spaced side frame members including vertical and horizontal reinforcing elements, end wall plates adjustably connecting the ends of said frame members, means for securing the end portions of said plates together in adjusted position, a hoist platform supported at the top of said frame structure, means for maintaining the platform centrally between the side frames of the structure during adjustment of the frame members including inwardly projecting plates lying in a common plane, said plates being formed with elongated slots, and fastening means carried by said platform and slideable in said slots, and a hoist mounted on said platform substantially centrally thereof, said hoist being retainable medially of the side frames due to the adjustability of the platform.

FRANCIS M. REISING.
